UNITED STATES PATENT OFFICE

AXEL PEDERSEN, OF MADISON, WISCONSIN, ASSIGNOR TO MADISON-KIPP CORPORATION, OF MADISON, WISCONSIN, A CORPORATION OF WISCONSIN

PRESSURE FLUID TOOL

Application filed September 16, 1931. Serial No. 563,202.

The present invention pertains to tools and particularly to those of the pressure-fluid operated type, wherein use is made of a turbine rotor.

5 It is the purpose of the invention to provide an extremely durable tool adapted for continuous and efficient service over long periods of time. Primarily the improvements relate to the design of the rotor and its arrangement in the tool body, so that maximum driving power is imparted to the rotor by the pressure fluid operating thereon. Thus, greater speed of the rotor-operated parts is obtained with no increase in fluid pressure, or lower fluid pressure may be used to produce any desired speed of operation.

10 Other objects and advantages of the invention will appear from the detailed description given below when read in connection with the accompanying drawing, wherein,

15 Figure 1 is a longitudinal section of one form of fluid-pressure operated tool embodying the invention.

20 Fig. 2 a section on line 2—2 of Fig. 1, showing the arrangement of the pressure-fluid inlet ports;

25 Fig. 3 a section on line 3—3 of Fig. 1, showing the construction of the turbine runner and its relation to the casing;

30 Fig. 4 a section on line 4—4 of Fig. 1, disclosing the manner in which the rotor shaft and its inner bearing are supported in the casing;

35 Fig. 5 a section on line 5—5 of Fig. 1, showing the similar manner of supporting the outer shaft bearing;

40 Fig. 6 a perspective of the improved turbine runner;

45 Fig. 7 a fragmentary section on line 7—7 of Fig. 1, showing the relation of one of the fluid inlet ports to the runner; and

Fig. 8 a section on line 8—8 of Fig. 1, disclosing certain details of the fluid control valve.

In the drawing the invention is illustrated as applied to a pressure-fluid operated tool of the general type covered by the pending applications of John R. Hoffman, Serial No. 419,417, filed January 8, 1930, and Serial No.

548,245, filed July 1, 1931. No claim is made herein to such features of construction and operation of the tool as are covered by these applications, but only to the improvements hereinafter pointed out.

55 As shown, the grinder comprises a tool casing 9 made up of a head portion 10 and a barrel portion 11. The head portion 10 terminates in a beaded end 12 threaded interiorly at 13. The outer end of barrel 11 also is 60 enlarged to form a smaller head portion 14 terminating in a beaded end 15.

65 Inferiorly of head portion 10, and preferably formed integrally therewith, are a plurality of inwardly projecting, radial ribs 16, the ribs being located at the juncture of the head portion 10 and barrel 11. The smaller head portion 14 also is formed with a similar set of radial ribs 17, the purpose of these two sets of ribs being to receive and properly 70 support in axial alignment certain rotor shaft bearings as explained hereinafter.

75 A plug-type closure member 18 is threaded into the open end of head portion 10, inward movement of the closure being limited by engagement of its face 19 with an annular shoulder 20 formed on the inside of the casing. The closure is provided with an axial bore 21 which connects at its forward end with a plurality of radial ducts 22 terminating in ports 23 on the face 19 of closure 18.

80 Rotatably mounted in bore 21 is a pressure-fluid control valve 24 provided with an adjusting knob 25. Valve 24 has an axial passage 26 therein which opens at one end 85 into the forward portion 27 of bore 21. At its rear end, passage 26 opens laterally for registry with a pressure-fluid inlet duct 28 when the tool is to be operated. A shoulder 29 in duct 28 provides for the support of a 90 suitable air strainer 30. A nipple 31, to which a suitable hose 32 is attached, is threaded into the outer end of duct 28.

95 A set screw 33 projects into bore 21 of closure 18, as shown in Figs. 1 and 8, and coacts with a cross groove 34 in valve 24 to prevent removal of the valve and to limit rotary movement thereof in both directions.

100 When knob 25 occupies the position shown, stop 33 engages one end of groove 34 and

inlet duct 28 is in direct communication with chambers 26 and 27, thereby delivering pressure fluid to radial passages 22. When however, knob 25 is rotated in the opposite direction until stop 33 engages the other end of groove 34, inlet port 28 is blanked by the stem of valve 24 and passage of pressure fluid to chamber 27 and radial ducts 22 is prevented. Obviously by suitable manipulation of knob 25, valve 24 may be moved into intermediate positions, whereby varying amounts of pressure fluid are supplied to chamber 27.

A rotor, comprising a shaft 35 and a runner 36, is mounted for rotation within the 15 tool casing 9. Runner 36 is formed on one face with a plurality of radial buckets 37 extending between inner and outer flanges or rims 38, 39, the buckets 37 being operatively related to outlet ports 23 in closure 18, as 20 shown in Figs. 1 and 8.

The important feature of the present invention, as stated, is the improved design of the turbine runner and its arrangement within the casing, so as to obtain maximum 25 driving power from the pressure fluid used. In order to utilize fully the velocity and pressure of the compressed fluid ejected from ports 23 into buckets 37, the operating clearance between the outer rim 39 of the runner and face 19 of closure 18 is reduced to a minimum. In practice, a clearance of 0.010 to 0.015 inches has been found to give the best results. The clearance between the inner flange 38 of the runner and the face of 35 closure 18 also is reduced similarly, thereby aiding further in the efficient operation of the tool.

With this arrangement, the pressure fluid acting on the runner is prevented by inner 40 flange 38 from escaping inwardly towards the axis of the runner, but, after exhausting substantially all of its kinetic energy in actuating the runner, escapes between outer flange 39 and the face of closure 18. The restricted, 45 annular exhaust passage formed by these parts tends to choke off or retard the flow of fluid from between the runner 36 and the opposed face of closure 18. As a consequence, the pressure fluid is retained between the 50 rims 38, 39 for a longer period, and full and complete use is made of its velocity head to operate the runner.

It will be noted that in the described construction the pressure fluid is fed to runner 55 36 at equi-spaced points from ports 23; also that the fluid, after acting on the runner, escapes uniformly about the periphery thereof. Furthermore, there are no exhaust ports located between the operating face of the runner and closure 18. Hence, steady operation 60 of the runner, because of the completely balanced action of the fluid thereon, is a feature of the tool.

Shaft 35 is rotatably mounted in a pair of 65 anti-friction bearings 40, 41. Only one of

these bearings will be described in detail, since they are of the same construction, although they are reversely arranged in the casing.

Balls 42 of inner bearing 40 cooperate with 70 inner ball race 43, secured to shaft 35, and an outer race 44, supported in notches 45 formed in ribs 16. Similarly, balls 46 of outer bearing 41 coact with races 47, 48, the latter being supported in notches 49 in ribs 17.

Shaft 35 is split at its outer end and threaded to receive a nut, thereby forming a chuck or tool-holding socket 50. It is also flattened at 51 to receive a wrench when a tool element 75 is being clamped in the chuck.

In order to lubricate bearings 40, 41 properly, shaft 35 is formed with a lubricant-receiving chamber 52 extending throughout its length. A rear set of radial ducts 53 and a front set of similar ducts 54 lead from chamber 52 into the interior of ball bearings 40, 41, respectively, so as to supply oil thereto from chamber 52 as a result of the centrifugal force acting upon the lubricant when the tool 80 is in operation. Lubricant is supplied to the passage 52 from the front end of shaft 35 inside of the chuck 50.

It is essential, because of the high speed of operation of this tool, that adequate provision be made to cool the bearings and also that the pressure fluid be excluded entirely from them so as to prevent the lubricant from being blown away. For this reason, both the front and rear bearings 40, 41 are protected by air deflecting washers 55, 56. Each washer 55 fits around the outside of the ball bearing and, in conjunction with an inner washer 57, forms an annular space to receive a felt packing 58. Each washer 56 is drawn out centrally at 59 to fit snugly about shaft 35 and prevent escape of lubricant from the bearing. Pressure fluid also is prevented from entering front bearing 41 by an annular air deflector 60 fixed on shaft 35 just to the rear of this bearing. With this arrangement, the exhaust fluid is deflected outwardly from bearing 41 and escapes between the bearing and casing 9 to the atmosphere through the spaces between ribs 17.

The rear end of lubricant chamber 52 is closed by a rivet 61 driven therein so that its head is flush with the end of shaft 35. The head of this rivet is hardened and cooperates with the hardened end of an adjustable screw 62 to form a thrust bearing for shaft 35. Screw 62 is threaded through face 19 of closure 18 and its slotted end is accessible through bore 21 when valve 24 is removed. A lock nut 63 is mounted on screw 62. It will be obvious that by proper manipulation of screw 62 and lock nut 63 any desired adjustment between the thrust bearing and shaft 35 may be effected.

The operation of the tool will be described now. Assuming that a quantity of oil has 130

been placed in chamber 52, a source of pressure fluid connected to hose 32, and that a tool element, such as a mounted grinding wheel, has been secured in chuck 50, when 5 valve 24 is moved to the position of Fig. 1, pressure fluid will enter passage 26. It then passes through chamber 27 to ducts 22 and escapes from ports 23, striking the blades of runner 36 and setting the rotor 10 in motion.

Entrance of pressure fluid into the central space between runner 36 and closure 18 is prevented by flange 38; hence, after 15 expending its force on the blades of the runner, it escapes around the outer flange or rim 39 into the chamber in head 10. The exhaust fluid then passes into cooling contact with the exterior of rear bearing 40 and between ribs 16. Here the fluid is divided into 20 a number of small streams which pass through barrel 9 and into intimate cooling contact with shaft 35. Deflector 60 and outer bearing 41 then are effectively cooled by the fluid as it passes around these parts 25 to the atmosphere.

The exhaust fluid completely encloses both bearings 40 and 41, and shaft 35 in a cooling bath, thereby absorbing and carrying away heat generated in the bearings and 30 cooling both the bearings and the lubricant. In escaping adjacent chuck 50, the exhaust fluid blows away any chips or dust produced by the cutting tool.

In the described construction, it is clear 35 that adjustment of the rotor may be varied readily to give proper operating clearances. Thus play and vibration are reduced to a minimum and operation of the tool is extremely quiet. The particular manner in 40 which the exhaust fluid is released from the tool renders unnecessary the provision of a special muffling device. The stringent requirements of extremely high speed operation are adequately taken care of by the 45 special bearing constructions for the rotor and the provision for their positive lubrication. These features ensure a device which practice has shown is capable of efficient and reliable operation over long periods of time.

While the improved rotor 36 and its arrangement in the casing have been illustrated and specifically described with reference to a certain type of tool, the invention 55 is applicable to tools of other types, and may be used for various similar purposes. For instance, its use has been found highly efficient as the operating means for the fluid distributing valve of tools of the type shown in the application of John R. Hoffman, Serial No. 512,446, filed January 30, 1931.

Although the preferred embodiment of 60 the invention is herein shown and described, it will be obvious that changes may be made

in the details thereof without departing from the spirit and scope of the invention, except as the same may be limited by the appended claims.

What is claimed is:—

1. The combination in a fluid-operated tool of a casing one wall of which is provided with a pressure fluid inlet port, said wall having no fluid outlet; a turbine runner mounted for rotation in said casing with one face thereof opposed to said casing wall; a series of buckets arranged on said face of the runner in operative relation to the inlet port; and an annular flange on said face of the runner around the series of buckets, the clearance between said flange and said wall being only sufficient to permit operation of the runner and affording the sole avenue of escape for pressure fluid operating on the runner. 70

2. The combination in a fluid-operated tool of a casing one wall of which is provided with a pressure fluid inlet port, said wall having no fluid outlet; a turbine runner mounted for rotation in said casing with one face thereof opposed to said casing wall; a series of buckets arranged on said face of the runner in operative relation to the inlet port; and an annular flange on said face of the runner around the series of buckets, the clearance between said flange and said wall being substantially 0.010 to 0.015 inches and affording the sole avenue of escape for pressure fluid operating on the runner. 80

3. In a fluid-operated tool, the combination of a casing one wall of which is provided with a pressure fluid inlet, said wall having no fluid outlet; and a turbine runner mounted for rotation in said casing with one face thereof opposing said wall of the casing, the runner being provided on said face with buckets and annular flanges closing the inner and outer ends of the buckets, there being only sufficient space between said flanges and said casing wall to permit operation of the runner, and said space affording the sole avenue of escape for exhaust fluid from the runner. 90

4. The combination in a fluid-operated tool, of a casing provided with a fluid inlet in one wall thereof and a fluid outlet, said casing wall having no fluid outlet; and a turbine runner mounted for rotation in said casing with one face thereof in closely opposed, parallel relation to said wall of the casing, the runner being provided on said face with buckets located opposite said fluid inlet and with inner and outer annular flanges closing the ends of the buckets, said flanges being spaced only sufficiently from said casing wall to permit operation of the runner and the clearance thereby afforded providing the sole avenue of escape for exhaust fluid from the runner to said fluid outlet. 100

5. In a fluid-operated tool, the combination of a casing provided with a fluid inlet 110

in a wall thereof, said wall having no fluid outlet; and a balanced turbine runner mounted for rotation in said casing with one face of the runner opposing said wall, the runner being provided on said face with buckets located opposite the fluid inlet and with an annular flange closing the outer ends of the buckets, the space between said flange and said casing wall being only sufficient to provide operating clearance for the runner and affording the sole avenue of escape for exhaust fluid from the runner.

6. In a pneumatically-operated grinder, the combination of a casing provided with fluid inlets in a wall thereof and a fluid outlet, said casing wall having no fluid outlet; a grinder shaft mounted for rotation in the casing; a turbine runner fixed to said shaft with one face of the runner disposed parallel to said wall of the casing, the runner being formed on said face with an annular series of buckets disposed in operative relation to the fluid inlets and with inner and outer flanges closing the ends of the buckets, the space between said flanges and casing wall being only sufficient to provide operating clearance for the runner and affording the sole passage for escape of exhaust fluid from the runner to the fluid outlet.

7. In a pressure-fluid operated tool, the combination of a casing having a fluid outlet and a wall provided with a fluid inlet; a rotor in said casing comprising a shaft and a runner thereon provided on its operating face with a series of buckets and inner and outer flanges closing the ends of said buckets, said buckets being disposed in operative relation to the fluid inlet and said flanges spaced from said casing wall only sufficiently to permit free rotation of the runner, the space between said wall and the outer flange affording the sole avenue of escape for exhaust fluid from the runner; a pair of ball bearings in which the rotor shaft is mounted, said bearings being located in line with the exhaust fluid from the runner to cool the bearings; lubricating means for the bearings; means for preventing exhaust fluid from forcing lubricant from the bearings; and means for controlling the supply of pressure fluid to the fluid inlet.

In testimony whereof I have signed my name to this specification.

AXEL PEDERSEN.
